FOOD PACKAGING TRAY

Frances G. Stamper, Houston, Tex., assignor to General Foods Corporation, White Plains, N.Y.

Filed Jan. 10, 1972, Ser. No. 216,901

Term of patent 14 years

Int. Cl. D9—03

U.S. Cl. D9—185

FIG. 1

FIG. 2

FIG. 1 is a top plan view of a food packaging tray showing my new design.

FIG. 2 is a top perspective view.

The bottom and opposite edge are substantially plain and unornamented.

I claim:

The ornamental design for a food packaging tray, substantially as shown and described.
